Primary Examiner — Catherine S Posthauer(74) *Attorney, Agent, or Firm* — Crose Law LLC;
 Bradley D. Crose(57) **CLAIM**

The ornamental design for a screw cap, as shown and described.

DESCRIPTION

FIG. 1 is a side view of a screw cap, showing my design; FIG. 2 is a top view thereof; FIG. 3 is a bottom view thereof; FIG. 4 is a top perspective view thereof; and, FIG. 5 is a bottom perspective view thereof.

The broken lines shown in the drawings illustrate portions of the screw cap and form no part of the claimed design.

1 Claim, 5 Drawing Sheets(56)
